UNITED STATES PATENT OFFICE.

ALFRED E. JONES, OF NEWARK, NEW JERSEY, ASSIGNOR TO HIMSELF AND JOHN T. ROWLAND AND ROBERT GRAY, JR., OF SAME PLACE.

APPARATUS FOR SEPARATING GOLD FROM QUARTZ AND ROCK-TAILINGS.

SPECIFICATION forming part of Letters Patent No. 251,718, dated January 3, 1882.

Application filed June 25, 1881. (No model.)

To all whom it may concern:

Be it known that I, ALFRED E. JONES, of Newark, in the State of New Jersey, have invented a new and useful Improvement in Apparatus for Separating Gold from Quartz and Rock-Tailings, of which the following is a specification, reference being had to the drawings herewith accompanying the same.

My invention consists in the arrangement and application of a suitable fibrous material in combination with machinery, so that the fibrous material will unite or collect to itself the gold and carry and deposit the same to a place designated, where it may be collected and treated as desired in separating the precious metal from its sand and ore.

Figure 1 is a side elevation of an apparatus embodying my invention. Fig. 2 is a top view of the same, and Fig. 3 is a sectional view of the vat employed, showing the agitator and separator, and also the draw V and the sliding bottom.

A and B are two rolls of suitable dimensions, superimposed one over the other, and held in position by the upright standard frame-work C'. These rolls run an endless broad belt or felt blanket, such as is ordinarily used by paper-makers. One side of said belt is led between the faces of a wire-cloth-covered drum or cylinder, F, and a roll, D, said roll D being covered by any soft material, by which a more perfect contact is obtained between the said blanket and the cylinder F. The said cylinder revolves in a vat or tank, E, (shown in section in Fig. 3.) The ends of the cylinder are open and abut against rings of wood, of the same diameter as the cylinder, fastened on the inside of the vat, so as to form a seat for suitable packing, to prevent the escape of any fluid or other material this way. Consequently the water to escape must pass through the wire-cloth, and thereby deposit on the wire-cloth any material it may have in suspension. This operation is substantially thus far the same as the operation of paper-making by the "cylinder-machine," so called.

G is a mixing-box to unite the fiber received from a tank, G⁶, with water which is received from the pump B⁴.

H H are boxes that receive the water from the cylinder F, and are provided with a gate over the opening, (shown at M² on sectional drawing,) to regulate the flow of water to the pumps B³ B⁴.

K is a pipe to return water to box H from the pan or save-all T under the rolls A B, the revolving of the rolls forcing the water out of the pulp carried to and between them by the belt C.

P is a settling-tank.

L is a catch-box to catch refuse flowing from settling-tank P.

M is a box into which pumps B⁴ and D⁴ both empty, D⁴ being a pump to force fiber from the tank G⁶, which fiber has been held in water in said tank, and so fiber and water are mixed together.

G⁶ is a tank for fiber which has not yet passed through the machine, and held in reserve.

N is a box where is united the water from pump B³ and pulp from tank G⁵ through the use of the pump D⁵.

P is a mixing and settling tank for the gold-tailings, receiving them mixed with water through pipe a² from a common pug-mill or direct from quartz-crushers, as the case may be. a' is the outlet-pipe for the same, discharging into box Q, where the tailings mix and unite with the pulp from box N, conveyed to box Q by means of the pipe B⁸.

R are screws bearing on rubber blocks u for forcing down the roll A.

S is a scraper for removing the pulp from roll A, and is pivoted and worked, as shown, by handle s, so as to be graduated in its pressing against roll A.

T is a save-all to catch the water from rolls A B.

V is a sliding box in bottom of vat E, and in which is a quantity of quicksilver at its bottom, designed to act as an amalgamating-pan, and also to receive heavy particles which may come over with the pulp and tailings, and enabling the same to be removed without stopping the operation of the machine by means of the movable slide W, (shown in sectional drawing.) It will readily be seen that when it is

desired to withdraw the pan V the handle y is worked back and forth till the plate W is slid over and covers the said sliding box.

X is an agitator to mix the pulp and tailings as they fall into the vat E.

Z are valves in bottom of settling-tank P, to remove refuse without stopping the operation of said tank. There are openings under the valves Z of settling-tank P, (not shown in these drawings,) through which refuse drops onto an apron under the tank P. As I claim this settling-tank in a separate application this day made to the Commissioner of Patents for the same, it is not necessary for me to refer to the same.

B⁵ is a pipe whereby water is conveyed from the pump B⁴ to the box M; B⁶, a pipe which leads to the tank G⁶. B⁷ is a pipe leading from box M to the mixing-box G.

P¹ P² P³ P⁴ are pulleys, on which runs the belt or apron C as it carries the fiber and metal to the scraper S and returns.

i is a sifter formed of the uprights, as shown in Fig. 3, whereby the heavier bodies of ore dropping into tank E are prevented from coming or crushing against the cylinder F.

The operation of my machine is as follows: Any fibrous matter that mixed with water will form a pulp is placed in the tank G⁶, and thus 30 thoroughly mixed is afterward pumped by pump D⁴ through pipe B⁶ into receiving-box M, and from there it flows through pipe B⁷ into the mixing-box G. The cylinder-wheel F, covered with a thin wire-gauze, such as will allow 35 water to flow through, but no pulp, revolves in box E, and, revolving, takes on its surface the pulpy matter. Ore-tailing is broken up into small pieces as possible by means of a pug-mill, and when so crushed and ground is passed 40 through the pipe a² into the settling-box P. This box is provided with partitions, each partition having an opening into the catch-box L, by means of button-bottoms, which are more fully described and set forth in my separate 45 application for patent of even date herewith, and to which reference is here made for a full description. As the ore passes through this settling-box all heavy lumps sink to the bottom and are drawn off. The lighter portions 50 and the precious metal float on the top, and are carried off through the pipe a' down into the box Q. This box Q has also graduated slides or bars, as shown in Fig. 3, over which the ore is carried, the heavier portions settling 55 to the bottom. The ore now passes from the box Q down into the receiving-vat E, which is nearly full of water, which is kept in constant agitation by means of the agitator X. The ore falling in this vat, all the heavier portions 60 sink into the drawer V, and by closing the bottom of the vat E over this drawer, as shown, by means of the movable piece W and wheel Y, the drawer V can be drawn out and emptied. The vat E has guards i, 65 (shown in Fig. 3,) which prevent the heavier portions of the ore coming into contact with

the wire-gauze wheel F. The wheel F being coated with pulp, and coming into contact with the ore or sand-tailings containing gold and water, the pulp takes up the gold onto its 70 surface and carries it up till it comes into contact with the broad endless woolen felt belt or blanket C. This blanket, revolving on the wheel D, takes off all the pulp and sand-tailings as they stick to it, and carries them 75 around with it over the pulley P' to and between the rollers A B. These rollers, being of wood or iron, are pressed tight down by means of the band-screw, so that all the water is 80 pressed out of the pulp containing the sand-tailings, which water flows into the save-all T, from thence flows through the pipe K into the box H, when it is pumped with the water that flows from the inside of the cylinder F into the box M, and from there into the mixing- 85 box G again. The pulp passed onto the roller A is carried up by it till it meets the scraper S, when it is cleanly scraped off and falls into a receptacle prepared for it. The blanket C thus passes over the pulleys P² P³ P⁴ to 90 wheel D, when it is again loaded up from the cylinder F. If the pulp is not charged sufficiently with the precious metal so as to pay to destroy or burn it, it is thrown into the tank G⁵ and thoroughly mixed again with 95 water, and from this tank pumped by pump D⁵ through the pipe into box N, thence through pipe B⁸ into box Q, and from there into the vat E, and thence around again. When the pulp is sufficiently charged with sand-tailings 100 it is taken and burned and the precious metal extracted.

B⁹ is another pump, situated at the opposite end of the cylinder F from that of B⁴, and is used to pump the water from box H' that flows 105 from that end of the cylinder F.

It will be observed that other ways may be employed rather than pumps for conveying the pulp from tanks G⁶ and G⁵.

What I claim, and desire to secure by Letters Patent, is—

1. In an apparatus for separating the precious metal from sand-tailings with fibrous material, &c., the combination of the tank G⁶, mixing-box G, cylinder F, vat E, endless belt C, rollers A and B, and scraper S, substantially as described, and for the purpose specified.

2. In an apparatus for separating the precious metal from sand-tailings, the combination of the tank G⁶, mixing-box G, cylinder F, vat E, endless belt C, with its pulleys, rollers A and B, and save-all T and its pipe K, scraper S, pump B⁴, box M and its connecting-pipes, and box H, substantially as described, and for the purpose specified.

3. In an apparatus for separating precious metal from sand-tailings, &c., the combination of the tank G⁵, pump D⁵, box N and its pipes, box Q, vat E, cylinder F, belt C and 130 its pulleys, and rollers A and B, substantially as described, and for the purpose specified.

4. In an apparatus for separating the precious metal from sand-tailings, &c., the combination of the tanks G⁶ and G⁵, mixing-boxes G and Q, vat E, cylinder F, pumps B⁴ and B³, with their pipes, belt C, with its pulleys, tank-boxes H and H', boxes M and N and their pipes, rollers A and B, save-all T and its pipe K, scraper S, agitator X, sliding bottom W and wheel Y, and pan V, substantially as described, and for the purpose specified.

ALFRED E. JONES.
